UNITED STATES PATENT OFFICE.

NAHO TANAKA, OF NEW YORK, N. Y.

TELEPHONE-TRANSMITTER.

1,288,743.

Specification of Letters Patent. Patented Dec. 24, 1918.

Application filed November 3, 1916. Serial No. 129,291.

To all whom it may concern:

Be it known that I, NAHO TANAKA, a subject of the Emperor of Japan, residing at New York, in the county of New York and State of New York, have invented new and useful Improvements in Telephone-Transmitters, of which the following is a full, clear, and exact description.

This invention relates to telephone transmitters of granular carbon type in which the vibratory part is yieldingly supported, or the vibrator is kept away from direct contact with hard fixed parts and a flexible sheeting (or auxiliary vibrators), except at 10 or with parts where such contact, if any, hinders only imperceptibly the required movement of the vibrator, so that certain undesirable effect upon the vibrator resulting from such contacts is minimized, and one 15 or more of carbon cells having a large combined area of electrode surface are employed.

The principal objects of my invention are, first, to minimize distorting effect in the 20 sound transmission as far as the transmitting apparatus is concerned; in other words, to faithfully translate vocal waves into electrical impulses, or at any rate to transmit sound vibration more agreeably than heretofore 25 tofore possible; second, to increase the current carrying capacity of the apparatus so that heavy currents may be advantageously employed or the apparatus, may be exposed to higher voltage currents than heretofore 30 possible without injury thereto; and third, to increase the resistance variability of the apparatus in high resistance circuits. The 35 further object is to provide apparatus of this class in which the granular carbon will 40 not become packed.

With the above and other objects in view, my invention comprises certain detail of construction and arrangement of parts, as will be hereinafter more fully described, 45 illustrated and claimed.

The invention will be best understood from the following description taken in connection with the accompanying drawings as reference, forming a part of this specification. However, I desire to have it understood that the apparatus herein shown is 50 merely illustrative, as the best embodiments of my invention as now thought, and that therefore I do not confine myself to any 55 strict conformity to the showing of the draw-

ings, but such changes and modifications may be made, when desired, as to fall within the scope of the invention as claimed.

In the drawings, similar characters of reference indicate corresponding parts, and in 60 which—

Figure 1 is a vertical sectional view of a telephone transmitter embodying my invention,

Fig. 2 shows another embodiment thereof 65 being a similar view, and

Fig. 3 is an enlarged view, showing the flexible connection of parts in Fig. 1.

Referring to the drawings, A designates a vibrator proper preferably of hard rubber 70 or other comparatively light material, which corresponds to a diaphragm in an ordinary transmitter, but has the freedom of vibration at its peripheral portion as well as at the center. 75

In Figs. 1 and 3, the vibrator A rigidly carries as a part thereof front electrodes B, each of which is electroplated and soldered to a shank b having a screw stem c that engages with small nuts e, e preferably of 80 light material on opposite sides of the vibrator. The screw stems c pass through the perforations of a flexible sheeting C, such as of mica or celluloid, and the sheeting C is yieldingly held between ring washers or 85 cushions D, E of felt or rubber or the like, which are in turn held between the nuts e and shanks b. The purpose of the employment of these cushions is to eliminate or minimize the distortive effect, on the vibrator, of the natural vibration of the sheeting C. 90

A back electrode part F in a plurally cup-shaped or depressed form, having back electrodes G at the cup bottoms, is disposed in 95 such manner that each of the front electrodes B confronts in parallel to the back electrode in a cup, leaving enough marginal space around its peripheral edge. The back electrode part proper may be made of metal 100 or carbon, but is preferably of insulating material, particularly, when desired to have each carbon cell insulated from the others so that the cells can be conveniently connected in series. The sheeting C is clamped 105 between the back electrode part and a guard plate d which has perforations similar to the front face of the back electrode part as readily understood from the drawings. The peripheral edge of the sheeting C is also 110

clamped between a front piece H and a guard ring i as shown. The front piece has a large aperture to receive a mouth piece J.

The spaces between the front and back electrodes are partly or fully filled with carbon granules or balls I, the ring cushions E sealing the spaces to prevent the carbon from leakage.

The necessary relative movement between the front and back electrodes is permitted partly by the flexing of the sheeting C, and partly by the yielding of the cushioning washers D, E. It is obvious that the double provision of flexibility or yieldability is desirable in order to lessen the resistance to the vibration of the vibrator and to partially relieve the stresses on the sheeting, and at the same time to make the cushions act as damping means for damping the vibrations of the vibrator, but that by employing a substantially inflexible sheeting, the cushions alone may be assigned to perform the function when desired.

The circumferential edge of the vibrator is preferably, though not necessarily, padded by a soft rubber band g to nearly close the air gap at that place. The terminals of the cells are led out to the screws f, f.

In Fig. 2, the arrangement of parts is reverse to that of Fig. 1, the vibrator part taking the form of the back electrode part of Fig. 1, and vice versa. A indicates a plurally cup-shaped vibrator having front electrodes B attached to the bottoms. Back electrodes G are secured to shanks with screw stems c which are secured to a back plate F by means of nuts e, e. The vibrator and the back plate are yieldingly connected by a sheeting C and cushions D, E, the sheeting being attached to the vibrator by means of a central screw f and a light collar h over the periphery. The back plate is preferably made of flexible material, and is secured to the casing H which has small openings at the front for admitting vocal waves to enter there-through. It is needless to state that the front or vibrator part should be made as light as possible to have least possible inertia thereof.

In the present instances, I have illustrated the forms having four variable resistance cells; however, the number of the cells may be varied, when so desired, and even a single cell may be employed in an instance, the cushions D, E may be applied on opposite sides of the sheeting or mica auxiliary diaphragm of a solid back transmitter.

From the foregoing description taken in connection with the accompanying drawings, in which I have illustrated the apparatus and the arrangements of parts as the best embodiments of my invention, the advantage of the construction and arrangements of parts and the methods of opera-

tion will be readily apparent to those skilled in the art to which this invention appertains.

Having thus described the invention, I claim:

1. In a telephone transmitter, an elastic connecting medium for opposing electrode bearers, comprising a sheeting, and cushioning washers disposed on opposite sides of the sheeting and held therewith together by one of the said bearers, the sheeting being rigidly attached to the other said bearer. 75

2. In a telephone transmitter, means for elastically connecting front and back electrode bearers, comprising a flexible sheeting attached to one of the said bearers, and yielding members between the sheeting and the other bearer, attaching means of the latter holding the sheeting and the yielding members together. 80

3. In a telephone transmitter, a yielding connection medium, comprising a sheeting and cushions for opposing electrode bearers, the said sheeting being rigidly attached to one of the said bearers and yieldingly to the other through the said cushions which are held between the sheeting and the latter bearer. 90

4. In a telephone transmitter, a mounting for a vibrator, comprising means connecting the vibrator to a front electrode, a sheeting secured to a support, and cushions disposed on opposite sides of the sheeting and held therewith together by the said means. 95

5. In a telephone transmitter, the combination with front and back electrode units, and a variable resistance medium between the said units; of a sheeting, and yielding washers on opposite sides of the sheeting, said sheeting being attached to one of the 100 said units and elastically connected to the other unit through the said washers. 105

6. In a telephone transmitter, the combination of a sheeting and cushions on opposite sides of the sheeting; with two opposing electrode parts, one directly and the other through the said cushions, attached to the sheeting, and granular carbon between the said electrode parts, all wholly supported by the sheeting. 110

7. In a telephone transmitter, two relatively movable parts, one having cup-shaped portions, an elastic sheeting attached to the cupshaped portions and yieldingly to the other of said parts, and granular carbon between the said parts. 120

8. In a telephone transmitter, a supporting sheeting, cushions, two relatively movable members attached to the sheeting, one directly and the other through said cushions, and granular carbon between the said members. 125

9. In a telephone transmitter, the combination with a casing, front and back electrode units, and variable resistance me- 130

dium; of cushions, and a sheeting connected to the casing and one of the said units, and yieldingly attached to the other unit through the cushions.

5 10. In a telephone transmitter, front and back electrode units, a casing flexibly connected to the back unit, a sheeting, cushions on opposite sides of the sheeting held therewith together by one of the said units, the

sheeting being attached to the other unit, 10 and granular carbon between the units.

In testimony whereof I affix my signature in presence of two subscribing witnesses.

NAHO TANNAKA.
